FRANZ LÖSEL, OF BRUNN, CZECHOSLOVAKIA.

ELASTIC-FLUID TURBINE.

Application filed August 26, 1924, Serial No. 734,357, and in Austria December 4, 1923.

This invention relates to elastic fluid turbines in which carrier bodies are provided for the guide blades or discs and particularly turbines having auxiliary or additional admission intakes at the intermediate stages.

The object of the invention generally is a turbine construction of this character wherein in the auxiliary intake or intakes are incorporated into the turbine structure in a manner to avoid the necessity of additional tightening and sealing devices, especially between the carrier bodies. A further object is a turbine structure of this character which is of simple construction and may be economically produced. To these ends I have devised a turbine in which the auxiliary intakes at the intermediate stages of the turbine are incorporated into and through the bodies carrying the stationary guide discs.

For a better understanding of the invention, reference may be had to the accompanying drawings, in which:

Fig. 1 is a longitudinal section of a turbine embodying the invention; and

Fig. 2 is a transverse section on the line I—I of Fig. 1.

Referring to this drawing, I have indicated a turbine consisting of a surrounding or outer casing *b* which carries the stationary guide nozzle carriers *h*, only one being illustrated for convenience in illustration. The carrier body *h* is of suitable form and is fastened in the casing *b* in any convenient manner, but preferably by having its periphery or its outer portion formed into a ring *d* which fits into a groove formed on the interior of the casing *b*. The ring *d* is observed to be slightly narrower than the width of the groove and a pair of rings *g* may be inserted around the sides thereof for tightening and retaining the carrier *h* with its ring *d* within the groove. The ring *d* is also provided on its periphery with a pair of V-shaped grooves *f* adjacent the opposite edges thereof, and in these grooves are placed a pair of rings *f* for assisting the rings *g* in holding the carrier *h* firmly and tightly in position. The casing *b* and the carrier *h* are provided with registering radial canals *a* and *c* for the admission of elastic fluid especially steam and these canals lead into a curved canal *e*, also formed in the carrier *h*, the latter leading into a stationary guide nozzle *k* formed in the same member in which the main stationary guide nozzle *k* is formed. The arrow *m* indicates

the direction of flow of the working steam from the admission or higher pressure stages and the arrow *n* indicates the flow of auxiliary steam through the canals *a*, *c*, *e* and *k*. The separate and distinct streams of elastic fluid, as steam, flow through the adjacent stationary nozzles *k* and *k*¹ but join together in the rotating bucket *L*; from whence they flow together throughout the remainder of the turbine. The bucket *L* is made large enough to receive steam from both canals *k* and *k*¹. The two streams in passing out from the stationary guide nozzles *k* and *k*¹ have to some extent an ejector action upon each other and the normal flow and expansion of the steam remains unimpaired by eddies, turbulences, etc. The canal *e*, *c* may be of any convenient form. The nozzle canals *k*, *k*¹ are preferably formed in uniform individual guide blade members which are assembled circumferentially about the turbine between the carrier body *h* and the guide discs *p* one after another on their circumferences. The nozzles *k*, *k*¹ are separated by the blade dividing part *o*.

A particular advantage of this construction is that no special tightening or sealing devices for the auxiliary intakes *a*, *c*, *e* is necessary,—the tightening means *f* and *g* serving the double purpose of sealing and retaining the carrier body *h* into the casing *b* and sealing against the escape of steam from the auxiliary steam intake *a*, *c*, *e*. Moreover the auxiliary steam in passing through the carrier body encounters surfaces which have already been heated to a certain temperature by the fluid in the turbine, thereby tending to increase the heat efficiency of the auxiliary steam which is taken in at the auxiliary stages.

Any suitable method of means may be devised for making a steam tight fitting between the stationary guide nozzle member *k*, *k*¹ and the carrier body *h*, as for example in the usual manner indicated.

Having thus described my invention, what I claim and desire to protect by Letters Patent is:

1. An elastic fluid turbine comprising a casing having an annular groove at the interior thereof, a plurality of sets of guide means, and a carrier body for said sets of guide means and having an outwardly projecting annular portion fitted into said groove, said casing and said carrier body be-

- ing provided with an auxiliary intake passage extending substantially continuously through said casing and the annular portion to the interior of said carrier body to supply 5 fluid directly to an intermediate set of guide means.
2. An elastic fluid turbine comprising a casing, a separate carrier body having its outer surface spaced from the inner surface 10 of the casing to admit fluid therebetween having an annular portion fitted substantially fluid tight in said casing, and an annular row of stationary guide means, said casing and said carrier being provided with at 15 least one auxiliary intake passage extending through said casing and said annular portion of the carrier to the interior of the carrier and guiding the elastic fluid directly to said set of stationary guide means.
- 20 3. An elastic fluid turbine comprising a casing, a separate carrier body fixed to the casing and having a connecting portion fitted fluid tight with the interior of said casing, and a plurality of annular sets of guide 25 nozzles fixed to said carrier body at the interior thereof, all of said guide nozzles having main guide canals and the guide nozzles of one of said sets having auxiliary guide canals adjacent the main guide canals, said 30 casing and carrier having an auxiliary intake passage guiding elastic fluid through the casing, said connecting portion and said carrier body direct to said auxiliary guide canals.
- 35 4. An elastic fluid turbine comprising a casing having an annular groove at the interior thereof, a plurality of sets of guide means for different stages of the turbine, a carrier body for said sets of guide means and 40 having an outwardly projecting annular portion extending into said groove, and sealing means in said groove on opposite sides of said annular portion, said casing and said carrier body being provided with 45 an auxiliary intake passage extending substantially continuously through said casing and the said annular portion to the interior of said carrier body and supplying fluid to one of said sets of guide means in an intermediate stage of the turbine.
- 50 5. An elastic fluid turbine comprising a casing; a separate carrier body spaced from said turbine casing to admit fluid therebetween and having an outwardly projecting annular portion fixed to the interior of the casing and stationary guide nozzles carried by said carrier body, having main guide canals and including an annular set of said 55 guide nozzles, in an intermediate stage of the turbine, having auxiliary guide canals adjacent the main guide canals, said casing and said carrier body being provided with an auxiliary intake leading fluid through the casing, said annular portion and said auxiliary canals.
6. An elastic fluid turbine comprising an outer casing; diaphragms; stationary nozzles arranged in annular sets, one on each diaphragm, and including a set at an intermediate stage of the turbine in which each 70 nozzle is provided with a main and an auxiliary canal; a separate carrier body spaced inwardly from said casing to admit steam therebetween and carrying said stationary nozzles and said diaphragms, and 75 connections between the outer casing and the carrier body, provision being made of an auxiliary elastic fluid intake passage extending through the outer casing, a portion of said connections and the carrier body and 80 guiding fluid to said auxiliary nozzle canals.
7. An elastic fluid turbine comprising an outer casing having an auxiliary fluid intake, and a separate rotor enclosing carrier body spaced from said casing to admit fluid therebetween having an elastic fluid canal associated with said auxiliary fluid intake, and diaphragms and corresponding sets of guide nozzles carried by and enclosed by said carrier body, said carrier body and the outer 85 casing having abutting surfaces and the canal extending from the outer casing and through said abutting surfaces directly through the carrier body to one of said sets of guide nozzles at an intermediate stage of 90 the turbine.
8. An elastic fluid turbine comprising an outer casing, a separate rotor enclosing carrier body therein carried thereby and spaced therefrom, diaphragms and corresponding 100 sets of guide nozzles carried by the carrier and including guide nozzles in an intermediate stage provided with auxiliary nozzle canals, and connecting and sealing means between the outer casing and the carrier body, provision being made of an auxiliary 105 intake passage extending through said outer casing and said carrier body and leading directly from the outer casing through the connecting means and between the sealing means into and through the carrier body, to enter said auxiliary nozzle canals provided in the guide nozzles at said intermediate stage.
9. An elastic turbine comprising an outer 115 casing having an auxiliary elastic fluid intake and a ring groove formed at the interior of said casing, a separate rotor enclosing carrier body spaced from said casing to admit fluid therebetween and having an 120 annular projection entering said groove and forming abutting surfaces therewith and annular sets of nozzles including an intermediate set of which the nozzles have auxiliary guide canals, provision being made of 125 an auxiliary intake extending through said outer casing and through said ring groove as well as through said annular projection and carrier body and leading to said auxiliary nozzle canals.

10. An elastic fluid turbine comprising an outer casing having a main elastic fluid intake and an additional elastic fluid intake leading to an intermediate stage, and a separate carrier spaced inwardly from said outer casing and mounted therein by means of a groove and an annular projection fitted in said groove and carrying the guide means of

said intermediate stage, said additional intake extending through said casing and carrier body and through such annular projection. 10

In testimony whereof, I have signed my name to this specification.

FRANZ LÖSEL.
